CIRCULAR WOOD BOX

Paul L. Blum, Marshfield, Wis., assignor to Blum Bros. Box Company, Marshfield, Wis., a corporation of Wisconsin

Application July 1, 1949, Serial No. 102,576

1 Claim. (Cl. 217—66)

1

This invention relates generally to the construction of wooden boxes and is directed primarily to improvements in circular wood boxes of the character used for the packing of heads of cheese.

The construction of round cheese boxes is fairly standard, each box consisting of a bottom and a top. Both the bottom and top are made in substantially the same manner in that each consists of a circular end wall of wood and a side wall made of at least two layers of laminations of wood veneer which are bent around the end wall and secured thereto by nails or staples. By reason of the use of nails or staples in making boxes of this character it is necessary that the walls be formed of relatively heavy or thick material, particularly the end walls in the edges of which the securing nails are driven. Unless such end walls are fairly thick the boards of which the end walls are made will split or there is a possibility of the securing nails passing through at an angle and projecting either from the top or bottom surface of the end wall.

The present invention has for a principal object to provide a new and novel method of securing the side walls of the body and top of a cheese box to the end walls which they enclose or encircle, whereby a strong and rigid construction is obtained and at the same time use may be made of boards for the circular end walls and of veneer sheets for the side walls, of materially lighter or thinner construction than the corresponding pieces at present made use of.

Another object of the invention is to provide an improved means of securing the side walls and end walls together in a circular box of the character stated, without the use of nails driven through the side walls into the edge of the end wall as is the present practice so that the possibility of splitting the boards of which the end wall is made up, is entirely eliminated.

Still another object of the invention is to provide a means for securing the laminated wood sheets forming the side wall of such a circular box or forming the wall for the lid thereof, to the edge of the end wall which such laminated sheets encircle, by means of a metal band which is first placed around the edge or periphery of the end wall and which is provided with outwardly directed spurs or securing elements which are forced through the veneer material forming the side wall and clinched to hold the side wall firmly in position against the edge of the end wall which it encircles.

A further object of the invention is to provide

an improved securing or coupling element for joining together an end wall and a side wall of a box of the character stated, which comprises a strip of channel material which encircles the end wall with the channel directed inwardly to receive the edge of the encircled wall, the bottom or web portion of such channel strip having triangular spurs punched therefrom which are forced outwardly and which are forced to penetrate through the laminated side wall as the latter is bent around the bottom wall, the outer ends of such spurs or securing elements being then clinched where they project through the laminated side wall to effectively lock the side wall and the bottom wall together.

The invention will be best understood from a consideration of the following detailed description taken in connection with the accompanying drawing forming a part of the specification, 20 with the understanding, however, that the invention is not to be limited to the exact details of construction shown and described since obvious modifications will occur to a person skilled in the art.

25 In the drawing:

Figure 1 illustrates in perspective the bottom portion of a circular cheese box constructed in accordance with the present invention and by the use of the improved securing means of the 30 present invention.

Figure 2 is a view in perspective of the top or lid for the box looking toward the inside thereof.

Figure 3 is a view in plan of an end wall for 35 either the bottom portion of the box or the lid thereof, showing the application to and around the periphery of the end wall of the side wall securing means of the present invention.

Figure 4 is a fragmentary view in elevation 40 of the outer side of a portion of the securing band looking toward the points of the outwardly extending securing spurs.

Figure 5 is a section taken substantially upon the line 5—5 of Figure 1 through a portion of 45 the lower part of bottom of the box showing the clinched end or point of a spur covered by a finish strip or band.

Figure 6 is a sectional view taken substantially upon the line 6—6 of Figure 2 showing the manner 50 in which the band secures the two laminations forming the wall of the top of the box.

Referring now more particularly to the drawing the numeral 10 generally designates the lower or bottom part of a circular cheese box 55 while the numeral 11 generally designates the

top or cover which is positioned over the bottom 10 to form the complete box in the well known manner.

In the bottom 10 the bottom or end wall is designated 12 and such wall comprises a plurality of boards *a* which are joined together in edge to edge relation and cut to the usual circular form. The side wall for the bottom 10 is designated 13 and this comprises two strips of wood veneer *b* which are laid one over the other with their ends slightly overlapped as indicated at *c* and these veneer strips are then bent around the end wall 12 to enclose or encircle the latter and in the customary manner of forming boxes, nails, not shown, are then driven through the wall 13 into the edge of the bottom or end wall 12 to secure the side wall 13 to the end wall. The ends of the veneer sheets are then brought into overlapping relation as illustrated and are joined together by securing nails or staples 15.

The lid or cover is constructed in a similar manner to the bottom part of the box except that the diameter is slightly larger so that the lid will receive the open top of the bottom part 10. The lid as here shown comprises the end wall which is generally designated 16, and the encircling side wall 17, such end and side wall being formed, as stated, in exactly the same manner as the bottom.

In view of the fact that the end wall and side wall for the bottom and top portions of the box are constructed in the same manner it will be understood that wherever, hereinafter, reference is made to an end wall or a side wall, either the end wall and side wall of the bottom part of the box or of the top part is meant.

In carrying out the present invention there is provided a band 18 of suitable length, formed of sheet steel of the desired weight or thickness, which band is of channel cross section as shown in Figures 5 and 6 and comprises the web or bottom part 18a and the edge flanges 18b. This channel strip of material is made of sufficient length to completely encircle the end wall with a slight overlap of the ends as indicated at 19. The overlapped ends are secured together and to the edge of the end wall by means of a nail or staple 20.

The center or web portion 18a of the channel band is punched or cut through at spaced intervals throughout its length along the two converging lines 21 whereby to form a substantially triangular, sharply pointed spur 22. This spur which is cut or punched from the web portion of the band, is bent to extend outwardly at right angles to the outer side of the web portion, being attached at the base of the triangle in the plane of a flange 18b.

When the band is applied to the circular end wall, it is applied so that the plurality of spurs 22 will extend outwardly from the plane of the inner surface of the end wall as shown in Figures 5 and 6, that is, when the band is placed around the end wall which is carried by the bottom part of the box the spurs will be in the plane of the top surface of such wall and when the band is applied to the wall 16 forming a part of the lid or cover the spurs will be in the plane of the undersurface of such wall.

The edge or periphery of the end wall will be received within the channel between the flanges 18b and after the band has been applied and secured the flanges will be pressed or forced into the wood to be substantially flush with the surfaces over which they lie, by the application of

suitable pressing rollers or other suitable means.

After the spur carrying band has been applied to the edge of the end wall the side walls or bands of veneer, after being placed one exactly on top of the other except for the end overlap as previously described, are then rolled and pressed onto the protruding points or spurs 22 which perforate the veneer walls, the ends of the points coming through slightly or projecting beyond the outer side of the veneer wall. The spurs or points are, of course, initially formed of suitable length to insure the projection of the points a slight distance beyond the outer side of the wall so that such points may then be bent over or clinched as indicated at 22a. The walls 13 and 17 of the lower part and the cover of the box, when rolled onto the points with the edges of the walls flush with the outer surfaces of the end walls, will be perforated and locked in place by the points at a distance from the outer surface of the end wall equal to the thickness of the end wall. After such application of the wall bands or veneer for the bottom or cover part of the box, the overlapping ends of the veneer bands are tacked together by the tacks or nails 15, as previously stated, in the conventional manner.

In the present invention, because the many steel points or spurs are thin, they decrease the tendency to split the veneer walls and also because they enter the wall relatively far from the edge of the veneer band and clinch so effectively, it is possible to decrease the thickness of the veneer band used in the box and cover. Thus it will be seen that by the employment of the present invention the wood pieces used for making the end walls may be made of materially lighter or thinner character than those at present used, where nails are employed for securing the veneer bands to the end walls and, for the reasons above stated, the veneers making up the bands may also be of materially less thickness than what is at present used.

It may be necessary in a very large heavily laden box, using the present invention, to resort to thicker end wall material and heavier and thicker veneers or bands to obtain the necessary strength of box to carry the load safely. In such event, however, it is still claimed that a saving in material for both the veneer walls and the end walls is effected to hold the load over what would be required for a corresponding load in a box of conventional type of construction.

With the present invention it is also possible to make round wood veneer walled boxes with a substantial saving in weight and material without sacrificing the strength and rigidity or appearance of the finished product. This is proven by the fact that the average conventional cheese box of a well known make weighs 4½ pounds, while a box of the same make and capacity using the present invention in its construction weighs very close to 3 pounds. The new type of box using the present invention in its construction, weighing two-thirds as much as the old, still is capable of performing the same service fully as well as the heavier conventional package.

I claim:

In a box for circular cheeses end walls and a side wall, one of said end walls constituting a permanent bottom and the other a removable cover, each of said end walls comprising several flat wooden pieces disposed in side edge-to-edge relation, a metal band of U-channel in cross section encircled about the outer edges of said pieces

with the said edges snugly engaged in the channel thereof, spurs struck out from the web of said band and projecting laterally outward in the plane of the upper side flange thereof, said side wall comprising two sheets of wooden veneer, one overlying the other, encircled about the bottom wall and having their side edge portions overlapped, fastenings engaged through the overlapping edge portions of said sheets, said spurs being passed through the bottom edge portions of said sheets and overturned to secure the sheets and the bottom wall together, and a band of the veneer encircled about the bottom end portion of the box and having a width to overlie the overturned ends of said spurs.

15 PAUL L. BLUM.
